UNITED STATES PATENT OFFICE.

HENRY RINGLERE, OF SPOKANE, WASHINGTON.

SPRING-HEEL.

1,175,083.

Specification of Letters Patent. Patented Mar. 14, 1916.

Application filed July 21, 1914. Serial No. 852,267.

To all whom it may concern:

Be it known that I, HENRY RINGLERE, a citizen of the United States, residing at Spokane, in the county of Spokane and State of Washington, have invented new and useful Improvements in Spring-Heels, of which the following is a specification.

This invention relates to spring heels, and it has for its object to produce a resilient device of simple and improved construction which may be readily applied to boots and shoes in the process of manufacture and which may be likewise readily applied to boots and shoes already made.

15 A further object of the invention is to simplify and improve the construction of the resilient device and to enable adjustment of the heel supporting plate to be effected.

20 With these and other ends in view which will readily appear as the nature of the invention is better understood, the same consists in the improved construction and novel arrangement and combination of parts which 25 will be hereinafter fully described and particularly pointed out in the claim.

In the accompanying drawing has been illustrated a simple and preferred form of the invention, it being, however, understood 30 that no limitation is necessarily made to the precise structural details therein exhibited, but that changes, alterations and modifications within the scope of the claim may be resorted to when desired.

35 In the drawing, Figure 1 is a vertical sectional view of the heel portion of a shoe equipped with the invention. Fig. 2 is a plan view of the heel plate detached. Fig. 3 is a side elevation showing the heel plate 40 and related parts detached and separated. Fig. 4 is a perspective detail view of the spring. Fig. 5 is a sectional view illustrating a modification.

45 Corresponding parts in the several figures are denoted by like characters of reference.

The shoe heel 15 is provided with a cylindrical recess 16 extending between the insole 17 and the bottom lift 18 of the heel. An aperture 19 arranged axially with respect to the recess 16 extends through the insole. A wear plate 20 is placed between the bottom lift 18 and the adjacent portion of the heel to support a coiled spring 21 which is 55 placed in the housing formed by the recess

16. Extending through the aperture 19 is a shank 22 carrying at its lower end a disk 23 and at its upper end a heel supporting plate 24 which, by the action of the spring, is supported a proper distance above the 60 insole.

As shown in Fig. 3, the shank 22 may include a threaded sleeve or nut 25 and threaded stems 26, 27 connected, respectively, with the heel plate 24 and the disk 23. This construction not only facilitates the assemblage 65 of the parts, but it also enables the heel plate to be adjusted at various distances above the insole, as will be readily understood, such adjustment being effected during the assembling of the parts.

Under the construction illustrated in Fig. 5, a metallic lining 28 is provided for the recess 16 that constitutes the spring containing 75 housing.

The operation and advantages of this invention will be readily understood from the foregoing description, taken in connection with the drawing. The device, as is obvious, may be readily applied to shoes in the 80 process of manufacture; when applied to shoes already made, the bottom lift is removed; a hole is bored through the heel extending to the insole, and the latter is provided with an aperture axially with respect 85 to the bore. The heel plate 24, disk 23 and assembling member 25 are now placed in position, it being obvious that the parts will be assembled in such fashion as to support the heel plate at the desired distance above 90 the insole. The spring 21 is now placed in position beneath the disk where it may be secured in any convenient manner, and the bottom lift 18 is finally restored. The weight of the wearer will depress the heel 95 plate at each step against the tension of the spring 21, thereby producing at each step a resilient action which facilitates walking and promotes the comfort of the wearer.

Having thus described the invention, what 100 is claimed as new, is:—

A shoe having a heel provided with a vertically extending recess and a bottom lift, a compression spring within the recess, an insole provided with an opening therethrough 105 in alignment with the vertical axis of the recess, and of less diameter than the recess, a heel plate located within the shoe above the heel, and a shank connected at its upper end to the heel plate and passing through 110

the opening in the insole and having a plate connected to its lower end and contacting with the upper end of the spring and arranged to contact with the insole and serve as a stop to limit the upward movement of the heel plate, the shank being provided with means to adjust its length.

In testimony whereof I affix my signature in presence of two witnesses.

HENRY RINGLERE.
